UNITED STATES PATENT OFFICE.

STEPHEN M. GRISWOLD, OF BROOKLYN, NEW YORK.

DESIGN FOR JEWELRY.

SPECIFICATION forming part of Design No. 18,601, dated September 11, 1888.

Application filed August 4, 1888. Serial No. 283,009. Term of patent 7 years.

To all whom it may concern:

Be it known that I, STEPHEN M. GRISWOLD, of the city of Brooklyn, in the county of Kings and State of New York, have invented and 5 produced a new and original Design for Jewelry, of which the following is a full, clear, and exact description.

My new design is fully illustrated in the accompanying drawing, to which reference is 10 made.

A B represent two concentric nearly semicircular curves of different radii and one within the other. Adjacent to the outer curve, A, appear the half-diamond-shaped figures *a a*, 15 and adjacent to the inner curve appear similar figures, *b*, smaller in size than the figures *a*. Between the curves A B appear the corrugations C, the crests or center lines, *c*, of which terminate at the points or angles of the half-diamond-shaped figures *a b*. The edges D D 20 are each straight for a short distance, as at *d*, and then formed in an irregular curve, *d'*, to the point *d''*, where they meet. Radiating from

this point are numerous irregular curves *f f*, equidistant apart between the edges *d' d''*. 25 These curves *f* join the corrugations C, and between said curves where they join the said corrugations C appear the semicircular series of openings *g*. Connected to the lower edges, *d d*, appear the diagonal pendants E E', of concatenated ovals united in a circle, *E'*, and from this ring leads another pendant, F, of concatenated ovals. 30

I claim—

The design for jewelry herein shown and described, the same consisting of the concentric semicircular curves A B, intermediate corrugations, C, straight and curved edges *d d'*, meeting at a point, the radiating lines *f*, meeting the corrugations, and the diagonal pendants 35 E E' and straight pendant F, substantially as described.

STEPHEN M. GRISWOLD.
